CONTAINER FOR ELECTRIC SHAVER KITS AND THE LIKE

Beverly B. Bond, South Norwalk, Conn., assignor to Ronson Corporation, Newark, N. J., a corporation of New Jersey

Application October 10, 1955, Serial No. 38,301

Term of patent 14 years

(Cl. D86—10)

Fig. 1 is an end elevational view of a container for electric shaver kits looking from the left of Fig. 2,

Fig. 2 is a side elevational view looking from the right of Fig. 1,

Fig. 3 is a perspective view, and

Fig. 4 is a bottom plan view.

I claim:

The ornamental design for a container for electric shaver kits and the like, substantially as shown.
